UNITED STATES PATENT OFFICE.

CHESTER A. COLVIN AND JOHN O. GODDARD, OF LITTLE ROCK, ARKANSAS.

SUBSOILER ATTACHMENT FOR PLOWS.

1,324,731.

Specification of Letters Patent. Patented Dec. 9, 1919.

Application filed February 11, 1916, Serial No. 77,704. Renewed October 16, 1919. Serial No. 331,217.

To all whom it may concern:

Be it known that we, CHESTER A. COLVIN and JOHN O. GODDARD, citizens of the United States, residing at Little Rock, in the county 5 of Pulaski, State of Arkansas, have invented certain new and useful Improvements in Subsoiler Attachments for Plows; and we do hereby declare the following to be a full, clear, and exact description of the invention, such as will enable others skilled 10 in the art to which it appertains to make and use the same.

The present invention is directed to improvements in subsoiler attachments for 15 plows, and has for its object to construct a device of this character capable of being readily attached to a conventional form of plow.

A further object of the invention is to 20 provide novel means for connecting the beam of the subsoiler attachment to the beam of the plow.

With these and other objects in view, this 25 invention resides in the novel features of construction, formation, combination and arrangement of parts to be hereinafter more fully described, claimed and illustrated in the accompanying drawing, in which:—

Figure 1 is a side elevation of a conventional form of plow, equipped with the device. 30

Fig. 2 is a rear elevation of the same.

Fig. 3 is a sectional view on line 3—3 of Fig. 1.

Fig. 4 is a top plan view of the subsoiler. 35

Fig. 5 is a sectional view on line 5—5 of Fig. 1.

Fig. 6 is a sectional view on line 6—6 of Fig. 4.

Referring to the drawing 1 designates a conventional form of plow including the usual curved beam 2, and to which the subsoiler is attached. 40

The subsoiler comprises a curved beam 4, 45 the lower end of which carries the landside 5 and moldboard 6. The upper end of the beam 4 terminates in a jaw plate 6, which rests flush against the ribs 7 on the right

hand side of the beam 4, while the ribs 8 on the left hand side thereof are engaged by 50 the clamping plate 9, the ends of which are connected to the adjacent ends of the jaw plate by bolts 10. Thus it will be seen that upon manipulating the bolts 10 that the beam 4 can be raised or lowered to regulate 55 the cutting action of the subsoiler.

To firmly brace the beam 4, a bar 11 is provided and has its lower end bolted to the beam 4 intermediate the ends thereof. A clamp 12 is provided and consists of complementary plates 13 having depressions 14, which when confronting, receive the beam 2. The ends of the plates 13 are connected by bolts 14, an additional bolt 15 being passed through the upper ends of said plates 65 and through the upper end of the bar 11, whereby the same is firmly clamped therebetween, as clearly shown in Fig. 5 of the drawing. It will be of course understood that the clamp 12 is adjustable on the beam 2. 70

It will be understood that the subsoiler cuts the earth below the furrow formed by the usual plow. The moldboard of the subsoiler forces the soil upwardly and rearwardly, after which it falls into the furrow 75 so that clay will be positively prevented from being deposited on the surface.

What is claimed is:—

A subsoiler attachment for plows comprising a pair of spaced clamping sleeves 80 adapted for engagement with the beam and standard respectively of a plow, a brace pivoted at one end to the former sleeve and a supplemental beam carried by the latter sleeve and having a standard into which it 85 merges and which is provided with a share, said brace being pivoted at its other end at the point of merger of said supplemental beam with its standard.

In testimony whereof we affix our signatures, in the presence of two witnesses.

CHESTER A. COLVIN.
JOHN O. GODDARD.
